UNITED STATES PATENT OFFICE.

GEORGE N. PALMER, OF ELMIRA, NEW YORK.

IMPROVEMENT IN COOKING-STOVES.

Specification forming part of Letters Patent No. **150,781**, dated May 12, 1874; application filed March 25, 1874.

To all whom it may concern:

Be it known that I, GEORGE N. PALMER, of Elmira, in the county of Chemung and State of New York, have invented certain new and useful Improvements in Cooking-Stoves; and I do hereby declare that the following is a full, clear, and exact description thereof, reference being had to the accompanying drawings, and to the letters of reference marked thereon, which form part of this specification.

The nature of my improvements consists in the peculiar arrangement of the dampers with relation to the oven and flue surrounding the same, as will be more fully set forth hereafter.

Figure 1 is a central vertical section. Fig. 2 shows a vessel with pipe connecting with the smoke-pipe.

A represents the oven of the stove, with front flue B, top flue B¹, rear or back flue B², and bottom flue B³. These flues all extend the entire width of the stove, and have no divisions or partitions, as is usual in what is known as "diving" flue stoves. C represents the firebox or chamber, located in front of the flue B, and above the same is the stove top D. D' is the top of the main part of the stove, above the top flue B¹, the stove being somewhat in the shape of what is usually known as a "step-stove." In the flue B¹, above the stove, is a perforated hinged damper, b, extending the entire width of the flue, and provided with a slide, d, for opening or closing the perforations in the damper. When the damper b is let down the flue B¹ is unobstructed, and the results are as above described. When the damp-

er is raised, and the slide d opened, a great proportion of the products of combustion will pass under the oven, dividing it equally, one-half above, and one-half below; and when the slide is closed they will all pass under the oven. At the upper end of the back flue B² is a sliding damper, f, which, when open, allows part or all of the products of combustion to pass under the oven, but when closed compels them to pass over the oven. This is specially of advantage in the summer-time, when less heating-surface is required.

It will be noticed that my stove is of the class known as "low-oven stoves," in which heretofore the products of combustion have not been made to pass from the fire-chamber down to the bottom of the oven.

Having thus fully described my invention, what I claim as new, and desire to secure by Letters Patent, is—

1. The hinged perforated damper b, provided with the slide d, and arranged in the top flue B¹, for the purpose of more thoroughly regulating the amount of heat in its passage around the oven, substantially as herein set forth.

2. The combination of dampers b, provided with slide d, with damper f, both being arranged in relation to each other substantially as shown.

In testimony that I claim the foregoing as my own I affix my signature in presence of two witnesses.

GEORGE N. PALMER.
